UNITED STATES PATENT OFFICE

HARRY C. DREIBUSS AND GEORGE S. CHILES, OF ST. LOUIS, MISSOURI, ASSIGNORS TO SCULLIN STEEL COMPANY, OF ST. LOUIS, MISSOURI, A CORPORATION OF DELAWARE

TRUCK BOLSTER

Application filed August 31, 1929. Serial No. 389,732.

This invention relates to improvements in truck bolster design and principally to the construction of a truck bolster whereby reinforcements are provided for the side bearing supports.

A customary design for truck bolster consists of a substantially truss shaped girder having an upper compression member and a lower tension member joined by vertical side walls resulting in an approximately rectangular transverse section. Supports are generally provided for the side bearings on the upper surface of the compression member adjacent to the ends of the bolster. The vertical load at the side bearings will be substantially close to the longitudinal center line of the bolster and it is therefore necessary to provide some form of reinforcement within the section of the truck bolster to prevent bending of the compression member. If a vertical rib is provided connecting the upper and the lower webs of the bolster the load will tend to bend both the upper web and the lower web and it is therefore desirable to transmit the load in some manner to the vertical side walls in order to resist the bending tendency of the upper and lower webs. Various methods of reinforcements have been proposed and in one form diagonal braces are provided which connect at their lower ends adjacent to the corners between the side walls and the lower tension member.

It is an object of the present invention to provide improvements in integral reinforcing means for the side bearings of a truck bolster whereby greater strength is provided.

It is further an object of the present invention to provide a construction of reinforcing means for the side bearings of a truck bolster which is economical in manufacture and adaptable to efficient casting of the bolster.

It is further an additional object of the present invention to provide bracing ribs located within the section of the bolster at the side bearings which are formed curved or corrugated in horizontal section in order to provide greater strength in resisting compressive loads.

Additional advantages will be more readily apparent from the following descriptions

taken in connection with the attached drawings, in which:—

Figure 1 is a partial plan view of a truck bolster in which a portion of the compression member has been broken away in order to more clearly illustrate the strengthening ribs for the side bearing support. 35

Figure 2 is a side elevation of the portion of the bolster illustrated in Figure 1.

Figure 3 is an end view of the bolster. 60

Figure 4 is a transverse section taken on the plane indicated by 4—4 in Figure 2.

Figure 5 is a transverse section similar to Figure 4 but illustrating a modification in the shape of the ribs. 65

Figure 6 is an enlarged plan view of the side bearing support of the bolster in which a portion of the compression member has been broken away to more clearly indicate the strengthening ribs which constitute a modification of the shape illustrated in Figures 1 to 4 inclusive. 70

Figure 7 is a side elevation of the portion of the bolster illustrated in Figure 6.

Figure 8 is a transverse section taken on a plane indicated by 8—8 in Figure 6. 75

Figure 9 is a partial plan elevation similar to Figure 6 but illustrating a further modification in the shape of the strengthening ribs, and 80

Figure 10 is a transverse section on the plane indicated by 10—10 in Figure 9.

The outline of the bolster may be generally of customary shape and comprises a substantially flat upper web or compression member 10, a lower web or tension member 11, connected by vertical side walls 12—12. The mid portion of the compression member 10 is formed with the usual integral center plate 13. Suitable ribs 14—14 may be provided, 85 extending between the upper and lower webs 10 and 11 to strengthen the support of the center bearing 18. Column guides 15 may be provided extending from the side walls 12 adjacent to the end of the bolster. Openings 16 and 17 may be provided in the upper web 10 of the bolster in order to lighten the construction. It is customary to form the bolster with the deepest section at the center, gradually reducing the depth towards the end of 90 95 100

the bolster. It is further customary to enlarge the width of the bolster from the center plate towards the ends thereof. It will be understood that the improvements to be described may be adapted to many different shapes of bolster without departing from the spirit of the invention.

The side bearing support 18 is generally indicated formed as a slightly raised flat surface of the upper web 10 of the bolster adjacent to the spring supports 19 comprising the ends of the bolster. The side bearings are adapted to receive the load transmitted from the supported car during rocking movement thereof. It is customary practice to employ roller bearings carried by the body bolster or otherwise secured to the car, which are arranged to travel upon the side bearing supports of the truck bolster. The vertical load at the side bearings is normally transmitted at the longitudinal center line of the bolster but may at times be nearer the side walls upon pivotal movement of the truck bolster relative to the car.

It is obvious that the upper web 10 of the bolster must be reinforced in some manner to provide proper strength to stand up under the impact due to the side bearing clearances and the full load acting upon the rolling of the car. In general practice vertical ribs have been provided within the truck bolster connecting the upper and lower webs at points beneath the side bearings. This construction is not desirable since the load upon the side bearings will tend to cause bending of both the upper and lower webs. It is therefore necessary to provide some means of reinforcement by which the load acting upon the side bearing at the longitudinal center line of the bolster will be transmitted to the vertical side walls of the bolster or to points adjacent thereto.

As one form of construction there may be employed a pair of ribs 20 and 21 disposed as illustrated in vertical section of Figure 4. The ribs 20 and 21 connect to the under surface of the compression member at points spaced at short distances from the center line of the bolster. The ribs 20 and 21 diverge towards their lower ends where they are connected to the inner surface of the bottom of the bolster. The lower corners of the bolster are rounded as indicated at 22 and 23. The ribs 20 and 21 connect to the web 11 adjacent to the points where the rounded corners 22 and 23 begin. The connections between the ribs 20 and 21 and the upper and lower webs are also provided with filleted corners as shown at 24.

It will be readily apparent that the strengthening ribs as shown in Figure 4 will tend to transmit the load towards the side walls 12 of the bolster. It will therefore not result in bending of either the upper or lower web.

In order to facilitate the manufacture a modified construction may be resorted to such as is illustrated in section in Figure 5 in which, the lower portion of the ribs 20 and 21 are straight as at 25 and 26 for a short distance upward from the lower web 11. In casting this form of bolster dry sand cores are placed along the inside bottom of the bolster and the straight portions of the ribs would then be made in the dry cores. It is usual to make the remaining portion of the inside of the bolster of green sand cores.

According to the embodiment disclosed in Figures 4 and 5 the ribs in horizontal section as illustrated in Figure 1 are substantially straight. A more desirable formation in order to provide greater strength may be such as is illustrated in Figures 6 to 8 inclusive, in which ribs 27 and 28 corresponding to the ribs 20 and 21 are evenly curved in horizontal section. Thus the ribs 27 and 28 are closest together at the transverse center line of the side bearings and are curved towards the side walls. It will be readily understood that the curved section of the ribs 27 and 28 will provide greater strength in resisting compressive stresses than the straight ribs shown in Figure 1. The curved webs could also be formed to include the improvements of Figures 6 to 8 by providing lower portions of the curved ribs vertical relative to the bottom web and upper portions diagonally disposed.

As a further modification in the formation of the reinforcing ribs the construction illustrated in Figures 9 and 10 may be resorted to. In these figures diverging ribs 29 and 30 are used which are curved only at their mid portions as indicated by the corrugations 31 and 32. The remaining portions of the ribs are straight similar to Figure 1. This construction prevents bringing the edges of the ribs too close to the side walls and permits easy casting of the bolster.

In all of the illustrated forms it will be apparent that there is provided a side bearing reinforcement which may be readily integrally cast with the bolster and will tend to transmit the vertical load upon the side bearings towards the rigid side walls of the bolster. As above described it is preferable that the ribs be curved or corrugated in order to develop greater strength with the minimum thickness of metal. It may also be preferable to form the reinforcing ribs at the lower portions vertically straight for a short distance above the inner bottom of the bolster in order to render the bolster more readily adaptable to carrying out casting operations.

It will be understood that only preferred embodiments have been described and that modifications and changes may be resorted to without departing from the spirit of our

invention as expressed in the appended claims.

We claim:

1. A bolster comprising an upper compression member, a lower tension member and substantially vertical side walls forming a substantially rectangular section, said compression member having a portion forming a side bearing support, strengthening ribs arranged within the section of the bolster extending from the compression member to the tension member, the lower ends of the ribs being closer to the side walls than the upper ends thereof and the ribs being curved in horizontal section.
2. A bolster having a top surface and side walls, a portion for receiving side bearing stresses on said top surface, reinforcing members for said portion extending diagonally downward from said top surface towards the side walls, said reinforcing members being curved in horizontal section.
3. A bolster having a top surface and side walls, a portion for receiving side bearing stresses on said top surface, reinforcing members for said portion extending diagonally downward from said top surface towards the side walls, said reinforcing members being corrugated in horizontal section.
4. A bolster comprising upper and lower webs and vertical side walls, side bearing supports formed on the top surface of said upper web, reinforcing means for each of said side bearing supports, said means comprising a pair of corrugated reinforcing ribs extending from said upper web to said lower web, said corrugated ribs diverging downwardly towards the side walls.
5. A bolster comprising upper and lower webs and vertical side walls, side bearing supports disposed on the top surface of said upper web, reinforcing members for said side bearing supports disposed within the section of the bolster, said members including diagonal portions and vertical portions parallel to the side walls of the bolster, the lower ends of the reinforcing members being closer to the side walls than the upper ends thereof.
6. A bolster comprising upper and lower webs joined by side walls, side bearings disposed on the top surface of said upper web, bracing members arranged within the bolster section beneath each of said side bearings, said bracing members comprising ribs having lower portions parallel to the side walls and upper portions inclined relative to said side walls.

Signed at St. Louis, Missouri, this 27th
day of August, 1929.
